CONNECTING FILM ENDS

Hugo Westerkamp, Cologne-Braunsfeld, Germany; vested in the Alien Property Custodian

Application April 18, 1939, Serial No. 268,646
In Germany May 6, 1938

2 Claims. (Cl. 154—42)

The invention relates to an arrangement for connecting under pressure two film ends coated with a solvent, the connecting of two film ends including in particular a sticking together of two film ends which is effected by applying to the adjacent surfaces of two film ends laid one upon the other a solvent which dissolves the film material, while the film ends are placed under pressure, if necessary with the application of heat, until the double film thickness has been reduced to the thickness of a single film by compression, while the surplus dissolved film material flows away.

The object of the invention is to provide an arrangement by the use of which the film ends are connected durably in a manner which is satisfactory in all respects, and which ensures in particular that the film also remains quite flat at the connecting point.

According to the invention, this is achieved with an arrangement for pressing the film ends together during the connection thereof. This arrangement comprises two clamping jaws which are pervious to air and exert the connecting pressure, and is based upon the fact that the film ends are connected together in a really satisfactory and durable manner and the film also remains completely flat at the connecting point, but only if the solvent has sufficient opportunity to escape during the application of the pressing force.

The solvent must not escape too rapidly, whilst also means must be provided to ensure that the force by which the film ends are pressed together is effective over the entire surface during the escape of the solvent. According to the invention, this is best achieved if the clamping jaws are traversed by a plurality of fine channels forming communication between the clamping surface and the outer surface of the clamping jaws, in particular the rear surface thereof. However, it is not essential that this communication should be direct, but the object of the invention can also be achieved with clamping jaws consisting of a material of spongy structure. Both a material traversed by fine channels and a spongy material have, when ground plane, a large effective pressure surface having many air channels through which the solvent escapes without too rapid an escape thereof having to be feared.

The favourable period during which the film ends coated with the solvent should be maintained under pressure and during which the solvent escapes, depends upon the film material employed, which may consist, for example, of celu-

lose acetate, cellulose nitrate or cellulose hydrate, and upon the solvent employed, which may be, for example, glacial acetic acid or the like, and may be determined readily by experiment. Since the escape of the solvent from the film connecting point is substantially a function of the physical conditions of the surroundings, the clamping jaws are surrounded, according to the invention, by a chamber provided with an arrangement for regulating the degree of the absorption of the solvent by the air, it being possible to effect this regulation in a known manner.

The drawing illustrates diagrammatically a construction of an arrangement according to the invention, by way of example.

The two film ends to be connected together are designated by 1 and 2. They are coated with a solvent and are either laid directly one upon the other as shown and so pressed together that the surplus material flows away, or they may, for example, be oppositely bevelled at their edges which are connected and joined together by pressure.

The pressing force is exerted by two clamping jaws 3, 4, the direction of pressure being indicated by arrows in the drawing. The clamping jaws are so fashioned that they assist the escape of the film solvent from the film connecting point and the evaporation and withdrawal of the solvent. For this purpose, the clamping jaws, which are plane ground on their clamping surface, are made pervious to air, the clamping jaws preferably being traversed by a plurality of fine channels which form a communication between the clamping surface and the outer surface of the clamping jaws, in particular their rear surface. In the drawing, these channels are diagrammatically represented in section by a few rectilinear channels, but the number of channels in the individual cross-sectional plane may be considerably greater than that shown, while finely reticulate channels may be employed instead of rectilinear channels. A material of spongy structure, namely a material having a plurality of small interstices separated from one another by fine partitions, through which the solvent may readily be diffused, is suitable for producing the clamping jaws.

The clamping jaws are surrounded by a casing 5 in which the degree of absorption of the solvent by the air is regulated. This regulation may be effected in many different ways. If, for example, the absorption of the solvent by the air is a function of the moisture of the air, fresh air may be taken in through an aperture 6 in

the casing 5 by means of a fan 7, the moisture content of the said air being regulable by means of drying dishes 8. The surplus air may escape at 9. However, the absorption of the solvent by the air may also be regulated in very many other ways, for example by directly feeding solvent to, or extracting solvent from, the air in the chamber.

I claim:

1. Device for connecting the ends of lengths of film, comprising a housing and two compression jaws located in the housing and between which the ends of the film lengths may be inserted in overlapped condition with a film solvent therebetween and by which jaws the overlapping portions may be compressed to the thickness of a single film and from between which the excess material may escape, said jaws having smooth, rigid and substantially plane surfaces for compressing engagement with the film lengths and having a porous structure throughout the area of overlapping formed by a multiplicity of closely spaced fine channels through which evaporated solvent may be gradually withdrawn directly from the contacted surface and discharged through the structure to the interior of the housing, said housing having openings in alignment with the jaw surfaces and through

which the ends of the film lengths may be introduced into the space between the jaws.

2. Device for connecting the ends of lengths of film, comprising a housing and two compression jaws located in the housing and between which the ends of the film lengths may be inserted in overlapped condition with a film solvent therebetween and by which jaws the overlapping portions may be compressed to the thickness of a single film and from between which the excess material may escape, said jaws having smooth, rigid and substantially plane surfaces for compressing engagement with the film lengths and having a porous structure throughout the area of overlapping formed by a multiplicity of closely spaced fine channels through which evaporated solvent may be gradually withdrawn directly from the contacted surface and discharged through the structure to the interior of the housing, said housing having openings in alignment with the jaw surfaces and through which the ends of the film lengths may be introduced into the space between the jaws, means for delivering vapor to the atmosphere within the housing whereby to regulate the rate of withdrawal of solvent through the jaws, and means for passing air through the housing.
